SPRAY DEVICE FOR LIQUIDS, THERMO-PLASTICS, MOLTEN METAL, OR THE LIKE

Wilhelm Kopperschmidt, Hamburg, Germany

Application April 27, 1950, Serial No. 158,448
In Germany November 11, 1949

18 Claims. (Cl. 299—86)

1

The present invention relates to spray guns preferably of the type for hot-spraying of such coating materials as paints, lacquers, synthetics, thermoplastics, molten metals, and other corrosion-resistant or insulating materials.

The primary object of this invention is to provide such a spray device in which the spray medium is continuously adjustably ejected by high hydraulic self-pressure from a spray chamber through an exchangeable nozzle having a round, flat, slotted, or other profile-shaped orifice and after ejection is passed through mechanical dispersing means arranged within a protective jet hood. The nozzle of the device, tapering off conically from the spray chamber toward its orifice, serves as seat for a concentrically guided and axially slideable valve needle with correspondingly shaped tip cross-section. The protective hood extending from the mouth of the nozzle either diverges funnel-like or extends tubular for a certain distance and diverges then.

The provision of mechanical dispersing and atomizing means is another object of this invention comprising one or more screens, screen-like walls, baffle plates, louvers, radially arranged fins, or the like arranged suitably in the path of the issuing spray within the jet hood; whereby undissolvable particles, abrasives or very viscous or sticky materials are additionally dispersed during spraying and so are transferred into a uniform protective coating.

Spray guns of conventional construction, serving to hot-spray lacquers, thermoplastics, or other corrosion-resistant spray mediums by application of compressed air or other gases under high tension have the disadvantage that the large quantities of gases necessary to achieve atomization of the spray medium, impinge upon the surface to be coated with such an impact that a considerable portion of the material sprayed rebounds from the surface and is carried into the surrounding atmosphere by the expanding gases, forming a fine spray fog in spray booth and work room, impairing health of workmen, and even creating explosive gases. To remove such gases, requires inconvenient suction and exhaust equipment in the spray room which is also expensive in installation and operation. Another drawback is that if such equipment is inadequate, other surfaces within the work rooms are loaded and soiled with spray medium. Furthermore, a continuous change-over of the surrounding atmospheric air by efficient exhaust equipment, especially during the cold season, represents a considerable and expensive burden on the heating plant by exhaust-

2

ing large amounts of heated air. High-pressure hot-spray apparatus at present in use, having self-contained electric drives and working with pressures of from 3000 to 6000 lbs. per sq. in., are generally of complicated design, difficult to handle, inconvenient, and in continuous usage therefore tiresome to the operator. Especially, when it is required to spray large quantities of material and considerable surface areas with thermoplastics, such known spraying apparatus become completely inadequate. When spraying materials which tend to form strings, such as, for example, thermoplastics, bitumen etc., with compressed air or gases, the relatively slow issuing hot spray-material particles are subjected to the cooling effect of the gases, emerging with considerable higher velocity, and are apt to draw strings of considerable length, chilling on the surrounding air, and giving the so-called "wool-formation" effect. Under such conditions the surface to be finished receives a very irregular and spotty coating.

The present invention has a further object to provide means to overcome some or all of the above enumerated shortcomings and to provide a relatively simple, generally applicable, and adjustable spray device for most diversified spray mediums which assures trouble-free operation and uniform ejection even of spray mediums having very unfavorable spraying qualities. An important feature of the present device is that it not considerably fumigates the atmosphere of the spray room and that therefore exhausting equipment need not be installed.

Other features and advantages of the present invention will become apparent from the following detailed description taken in connection with the accompanying drawings showing diagrammatically a preferred embodiment of the invention and in which:

Fig. 1 is a longitudinal section of a spray device, wherein the upper half indicates a form in which no mechanical dispersing means are interposed in the path of the spray jet issuing from the nozzle; and the lower half indicates the mechanical dispersing means as interposed in the jet path according to the present invention; and

Fig. 2 is a section on the line 2—2 of Fig. 1 through the spray chamber with valve needle adjusting means.

On the drawing the same numerals refer to the same parts throughout and the device shown consists of a pressure-proof housing 1 with a cylindrical bore forming a spray chamber 2 which is adapted to receive and guide a valve needle 3,

Toward the ejection end cylindrical spray chamber 2 expands into a conical portion with sealing surface 4 which in turn is adjoined by a larger cylindrical bore with inside-threads 5 into which is screwed spray nozzle 6 with a hexagonal extending portion 7 adapted for application of a wrench. Spray nozzle 6 serves simultaneously as left-hand end wall of spray chamber 2. Needle 3 has two annular guide collars 8 with perforations to allow free passage of spray medium. Collars 8 guide needle 3 concentrically in relation to nozzle 6 in its axial movement within chamber 2. Nozzle 6, having a chamfered face 9, is tightly screwed against sealing surface 4 within housing 1 providing a pressure-tight closure of chamber 2 at this point. A short shaft 10 enters through cylindrical housing wall tangentially into spray chamber 2, said shaft having projections or cams 11 fixed in spaced relation to its inside end which engage the collars 8 of needle 3 (see also Fig. 2). The outside extension of shaft 10 carries a trigger 12 by means of which needle 3, extending with its tapered and pointed portion 14 into a correspondingly shaped seat in nozzle 6, may be raised off its seat against the resilient action of a spring 13 or the like, and the effective opening of the spray orifice may so be changed as required. In closed position of the device, spring 13 presses the tapered portion 14 of needle 3 against its seat in nozzle 6 whereby pressure-tight closure of spray chamber 2 is assured. The tapered seat in nozzle 6 is adjoined toward the outside, by a round, flat, slotted, or otherwise shaped ejection orifice or mouth-piece 15.

A spray medium supply line 17 connects to a supply opening 16 in housing 1 leading radially into spray chamber 2 through which hot spray medium is fed into said chamber under high self-pressure. A jacket line 20, surrounding line 17, carries hot oil, hot gases, or other heating means, to keep the spray medium in line 17 from chilling and congealing. A return line 43 through which spray medium not ejected through nozzle 6 may flow back, is connected to another passage 42, leading also radially into spray chamber 2 but angularly displaced against passage 16. This line is also heated by heating means within jacket line 44 for the same reason as line 17. Jacket line 20 has connection to a radial opening 18 which is axially spaced in relation to passage 16 and joins an axial passage 19 leading into an annular deep groove 21 which in turn has connections with a number of passages 22 arranged in spaced relation within the circumferential portion of housing 1 around spray chamber 2. Said passages have substantially axial or helical direction and join with their other end a chamber 23 at the rear end of housing 1 from where a line 24 establishes connection with jacket line 44; the latter connection not being indicated on the drawing. Annular groove 21 is covered by a flat ring 25. All passages serve to permit circulation of heating medium around the spray chamber so as to keep its content hot. Outside threads 26 are cut around the front portion of housing 1 onto which a protective jet hood 27, 28 is screwed. This jet hood has a cylindrical portion 27 and is preferably used in connection with additional mechanical dispersing means indicated at 31 and to be described later. The protective jet hood is preferably provided with thermo-insulated heating means 45 arranged within the hood walls when the de-

vice is intended to spray thermoplastic materials. Suitably spaced around the hood wall are one or more circular pipes 29 into which hot or burnable gas may be introduced through a supply line 30. The circular pipes 29 have suitable perforations directed toward the inside of the funnel-like hood or toward the front opening, so the gas issuing from said perforations, either burning or only hot, may impinge upon the surface being coated or upon the issuing spray, to affect the spraying process beneficially in some way. If conditions require, it is also possible to introduce cold or heated protective gases, through line 30 and circular pipes 29 with their perforations, into hood 27, 28 and so, if applying hot gases for example, prevent string-forming tendencies of the spray medium. The same means may serve furthermore, to protect issuing and dispersing spray medium against cooling-down or other disturbing influences by enveloping the spray in protective warm or hot gases.

This invention provides that certain spray mediums, which are not sufficiently dispersed when issuing from the nozzle, may be subsequently dispersed and atomized by mechanical means within the protective hood, 28. These dispersing means may comprise one or more screens, screen-like walls, louvers, baffle plates, radial fins or the like suitably arranged within said hood. Spray medium, ejected from the nozzle through a suitable orifice in a circular or flat jet with a self-pressure of about 140 lbs. per sq. in., is hurled with high velocity against such screens or baffle plates, whereby a very intensive dispersion and atomization is effected. The mechanical dispersing means 31 are preferably removable and exchangeable, and for certain applications also heatable. It is also advisable to provide means for tilting, so that adjustment in relation to the direction of the issuing jet is possible and so a position may be selected which in each instance effects most favorably a certain spray medium applied and suits the prevailing conditions best. Kind of screen, mesh of wire, size of baffle plates, and other factors have to be properly chosen to obtain best spraying results.

As may be seen in Fig. 2, shaft 10 enters with its extremity 32 into a socket hole 33 in housing 1 where it is rotatably confined and resiliently urged toward the left as viewed on the drawing, by spring 39. At its other extremity, located outside housing 1, shaft 10 carries manipulating means such as a trigger 12. The portion of shaft 10, passing through the wall of housing 1, is surrounded by a bushing 34 which is screwed into the housing with threads 35 and tightly sealed by a packing ring 36. Bushing 34 is of such a size that all parts secured to shaft 10 inside the housing may be removed with said shaft when bushing 34 is unscrewed. An inner sealing between shaft 10 and bushing 34 is obtained by radial sealing surface 38 on bushing 34 and an annular collar 37 tightly fitted on the shaft and resiliently urged against surface 38 by spring 39, which presses the surfaces firmly together. Additional sealing between shaft 10 and bushing 34 is provided in form of a stuffing-box with packing 40 and cap-nut 41 on the outside of the housing. The cams 11, operatively engaging the annular collars 8 on valve needle 3, are so shaped that in one position of shaft 10, needle 3 with its collars 8 may be axially removed toward the nozzle end.

Spray nozzle 6 (see Fig. 1) may have a slotted or oblong orifice whose width may be continu-

ously changed by an eccentric arrangement and adjusting screw or other suitable means (not shown). Spray chamber 2 may be kept at uniform working temperatures by circulating spray medium, hot gases or hot oil through the passages around the spray chamber, or by electric heating means.

The mechanical dispersing and atomizing means 31 in the path of the issuing spray may have concave, convex corrugated, or other suitable configuration; or they may be tilted in some manner to favorably influence dispersion into an exceedingly fine spray. They may be heated when spraying thermoplastics, bitumen or the like to prevent clogging of their perforations.

It is advisable to provide spray chamber housing 1 with thermoinsulated handles which in addition are protected by suitable shielding against radiant heat of spray medium and heating means. The handles with shields are preferably universally adjustable and tiltable in any direction in relation to the body of the spray device, so the operator is protected from the heat in all possible positions in which the device may be applied when spraying surfaces difficult of access or overhead surfaces.

In hot-spraying certain spray mediums, it may suffice to apply back flowing spray medium for heating or heat maintaining of the material in the feed line 17. The material return line 43 is not used in such cases but the excessive material supplied into chamber 2 is fed back through jacket line 20. Heating medium, if such should be additionally required to effect temperature rise within chamber 2, is in such cases fed and returned through another double line. Heating and heat maintaining of one medium by another may also be accomplished in such a manner that the medium to be heated flows in the jacket line and the heating medium in the inner line.

Handling and operation of the device is as follows: The valve needle 3, which is axially and concentrically guided within cylindrical spray chamber 2, presses under influence of spring 13 with its tapered pointed portion 14 against its seat in nozzle 6, thereby closing spray orifice 15 tightly. As soon as by manipulation of trigger 12, shaft 10 and its cams 11, coating with annular collars 8 on needle 3, are somewhat rotated against the tension of spring 13 needle 3 is lifted off its seat and nozzle orifice 15 is opened. Spray medium, maintained under high pressure within spray chamber 2, issues with high velocity through the opening so created. When working with easily dispersable spray mediums such as lacquer, paint, or the like, an arrangement without any mechanical dispersing means is sufficient. Such mediums issue from the nozzle in a circular, flat, cone-shaped, or fan-shaped jet, depending on the shape of the orifice, and expand into a fine spray. By proper manipulation of trigger 12 the spray jet can continuously be adjusted or be interrupted at any time.

When spraying inconsistent, tough or abrasives containing spray mediums, as, bitumen for example, it is advisable to apply additional mechanical dispersing and atomizing means as indicated at 31. More than one screen of properly selected wire mesh may be arranged axially behind each other. It is at the same time advisable to provide for adjustable arrangement of screens or baffle plates so the distance from nozzle 6 and their inclination in relation to the spray jet may be easily changed to suit varying condi-

tions and achieve adaptability to various spray mediums. To prevent clogging of screens or baffle-plates with congealing material, it is advisable to provide for heating them additionally by hot air, hot oil, or electrically when hot-spraying thermoplastics or the like. The spray medium is fed through heatable hoses under hydraulic self-pressure of about 140 to 5500 lbs. per sq. in. into spray chamber 2 which is pressure-tightly closed until valve needle 3 is retracted by manipulation of trigger 12.

The hexagon head 7 of nozzle 6 permits a ready removal and exchange of nozzle 6 by application of a socket-wrench. With nozzle 6 removed and shaft 10 with cams 11 in a suitable position, valve needle 3 may be axially removed and exchanged. Spray chamber 2 can then be cleaned without difficulty. Control shaft 10 with cams 11 can be readily taken out as a unit with bushing 34 by unscrewing the latter. Features of easy disassembling and cleaning are very essential in a spray device, especially when it is necessary to change from one spray medium to another very often. Easily detachable fastening means for jet hood 27, 28 and screens or baffle plates 31 for cleaning and exchange, are other advantages of the present spray device. The provision of thermo-insulated handles with adjustable shields facilitates use of the present spray device even under such adverse condition as high working temperature of the spray medium and prevents annoyance to the operator from the heat radiated by the device. Thus, it represents no problem to hot-spray ceilings, inside walls of containers, and other surfaces difficult of access.

While the invention has been described with reference to a particular embodiment thereof it will be understood that changes in arrangement and construction of parts be made without departing from the spirit and scope of this invention.

What I claim is:

1. A spray device of the character described including a pressure-resisting spray chamber, a spray nozzle in one end wall of said spray chamber, a protective jet hood on said end wall and surrounding said spray nozzle, mechanical jet dispersing means within said hood, an inlet passage for spray medium to said spray chamber, a valve needle axially slidable within said spray chamber, a control shaft with attached actuating means, means on said valve needle engaging said actuating means, a removable bushing surrounding said control shaft at the point of its penetration through the chamber wall, an annular sealing surface on said bushing and a sealing surface in said chamber wall coating with said annular sealing surface, said bushing being of such a size that said control shaft with attached actuating means can be withdrawn after removal of said bushing.

2. A spray device as specified in claim 1, in which said removable bushing, surrounding said control shaft, is provided with a stuffing-box for additional sealing between bushing and shaft.

3. In a spray device of the character described, a pressure-resisting spray chamber, an inlet passage for spray medium, a spray nozzle inserted in one wall of said spray chamber having an ejection orifice, a valve needle axially slidable within said spray chamber, actuating means for axial movement of said valve needle, a jet hood detachably secured to said spray chamber and projecting funnel-like from the wall into which said spray nozzle is inserted and surrounding the latter, and

mechanical spray dispersing means inside of said hood and in the path of the issuing spray jet, said mechanical spray dispersing means being adjustable in the direction of the issuing jet.

4. A spray device as specified in claim 3, in which said mechanical spray dispersing means is heatable, and detachably secured to the jet hood.

5. In a spray device of the character described, a pressure-resisting spray chamber, an inlet passage for spray medium, a spray nozzle inserted in one wall of said spray chamber, a valve needle axially slidably within said spray chamber, actuating means for operatively sliding said valve needle in relation to said spray nozzle thereby opening or closing said nozzle, and passages for heating means in the walls of said spray chamber.

6. A spray device as specified in claim 5 in which said heating medium passages run substantially parallel to the axis of said valve needle and said spray chamber and are spaced-apart around the circumference of said chamber, and annular passages at both ends of said chamber in communication with said passages and connected one to the inlet and the other to an outlet passage.

7. In a spray device of the character described, a pressure-resisting spray chamber, an inlet passage for spray medium, an outlet passage for spray medium, a spray nozzle inserted in one wall of said chamber, a valve needle axially slidably within said chamber, actuating means for operatively moving said valve needle, a protective jet hood detachably secured to said chamber, and heating means for said inlet and outlet passages and the connecting lines, said heating means forming part of the connection between said inlet and outlet.

8. A spray device as specified in claim 7, further characterized in that said heating means comprise jackets surrounding the inlet and outlet passages and lines.

9. In a spray device for hot and cold liquids, thermoplastics, and molten metal, a pressure-resisting housing, a pressure chamber within said housing, means for feeding spray medium under high pressure into said chamber, a spray nozzle in the wall of said chamber, a protective jet hood adjoining said housing around said spray nozzle, mechanical dispersing means in said hood, and means for regulating the opening in said spray nozzle.

10. A spray device as specified in claim 9, said nozzle regulating means comprising a needle valve, a stem on said valve needle, guiding means for said stem, and means for moving said stem longitudinally, said stem being located entirely within said pressure chamber.

11. A spray device as specified in claim 1, including bearings and guiding means for both ends of said control shaft, and resilient means urging said control shaft axially against said annular sealing surface of said bushing.

12. A spray device as specified in claim 1, in which the actuating means attached to said control shaft and engaging said valve needle are so shaped as to release said valve needle in one angular position of said control shaft.

13. A spray device of the character described, including a pressure-resistant spray chamber, a spray medium supply connection, a spray nozzle detachably and pressure-tightly joined to said spray chamber, a valve needle axially slidably and completely enclosed within said spray chamber for cooperation with said spray nozzle, actuating means for said valve needle, and means on said valve needle engaging said actuating means, said

detachable spray nozzle upon removal leaving an opening in the front end of said spray chamber large enough to permit removal therethrough of said valve needle with its means for engaging said actuating means.

14. A spray device as set forth in claim 13, in which said actuating means include a control shaft mounted transversely of said valve needle within said spray chamber and extending through the wall thereof so as to be operable from the outside.

15. In a spray device of the character described, a pressure-resistant spray chamber, an inlet passage for spray medium, a spray nozzle inserted in one wall of said spray chamber, a valve needle axially slidably within said spray chamber, a control shaft, actuating means for said valve needle on said control shaft, means on said valve needle engaging said actuating means, a jet hood detachably secured to said spray chamber and projecting from the wall into which said spray nozzle is inserted, mechanical spray dispersing means within said hood in the path of the issuing jet, and said hood expanding substantially funnel-like outwards from said spray dispersing means.

16. In a spray device of the character described, a pressure-resistant spray chamber, an inlet passage for spray medium, a spray nozzle inserted in one wall of said spray chamber, a valve needle axially slidably within said spray chamber, a control shaft, actuating means for said valve needle on said control shaft, means on said valve needle engaging said actuating means, a jet hood detachably secured to said spray chamber and projecting from the wall into which said spray nozzle is inserted, heating means in said jet hood, mechanical spray dispersing means within said hood in the path of the issuing jet, and said hood expanding substantially funnel-like outwards from said spray dispersing means.

17. In a spray device of the character described, a pressure-resistant spray chamber, an inlet passage for spray medium, a spray nozzle inserted in one wall of said spray chamber, a valve needle axially slidable within said spray chamber, a control shaft, actuating means for said valve needle on said control shaft, means on said valve needle engaging said actuating means, a jet hood detachably secured to said spray chamber and projecting from the wall into which said spray nozzle is inserted, mechanical spray dispersing means within said hood in the path of the issuing jet, said hood expanding substantially funnel-like outwards from said spray dispersing means, and suitable pipe lines in said jet hood having perforations for the purpose of ejecting pressure gas or flames into said hood.

18. In a spray device of the character described, a pressure-resistant spray chamber, an inlet passage for spray medium, a spray nozzle inserted in one wall of said spray chamber, a valve needle axially slidable within said spray chamber, a control shaft, actuating means for said valve needle on said control shaft, means on said valve needle engaging said actuating means, a jet hood detachably secured to said spray chamber and projecting from the wall into which said spray nozzle is inserted, mechanical spray dispersing means within said hood in the path of the issuing jet, said hood expanding substantially funnel-like outwards from said spray dispersing means, suitable pipe lines in said jet hood having perforations for the purpose of ejecting pressure gas or flames into said hood, and said perfora-

tions in said pipes being arranged so as to cause the ejected gases to form a gaseous protective jacket against atmosphere influence around the issuing spray jet.

WILHELM KOPPERSCHMIDT.
